[57] CLAIM

The ornamental design for a faucet body, as shown and described.

DESCRIPTION

FIG. 1 is a top, front and left side perspective view of a faucet body showing our new design;
 FIG. 2 is a left side elevational view thereof, the right side elevational view being the same in appearance;
 FIG. 3 is a top plan view thereof;
 FIG. 4 is a front elevational view thereof;
 FIG. 5 is a rear elevational view thereof; and,
 FIG. 6 is a bottom plan view thereof.
